DESIGN FOR A HAIR BANDEAU

David Baxter, Chicago, Ill.

Application April 2, 1945, Serial No. 118,812

Term of patent 14 years

(Cl. D86—10)

To all whom it may concern:

Be it known that I, David Baxter, a citizen of the United States, residing at Chicago, in the county of Cook and State of Illinois, have invented a new, original, and ornamental Design for a Hair Bandeau, of which the following is a specification, reference being had to the accompanying drawing forming a part thereof.

Fig. I is a perspective view of a hair bandeau embodying my new design.

Fig. II is a front elevational view; and
Fig. III is a side elevational view thereof.

I claim:

The ornamental design for a hair bandeau, substantially as shown.

DAVID BAXTER.
